United States Patent Office.

CHARLES R. BROADBENT, OF BOSTON, MASSACHUSETTS.

Letters Patent No. 64,277, dated April 30, 1867.

IMPROVEMENT IN SLIPPERS.

The Schedule referred to in these Letters Patent and making part of the same.

TO ALL WHOM IT MAY CONCERN:

Be it known that I, CHARLES R. BROADBENT, of Boston, Suffolk county, State of Massachusetts, have invented a new, useful, and improved Shoe or Slipper made of paper; and I do hereby declare the following description and accompanying drawings are sufficient to enable any person skilled in the art of making shoes to make my improved paper shoes without further invention or experiment.

The nature of my invention consists in making a shoe or slipper of paper by cutting out the upper or top and soles similar or in the same manner that leather and cloth are cut, and then putting the parts together on a last by pasting, cementing, sewing, or otherwise, so as to form the shoe or slipper. In the accompanying drawings—

Figure 1 is a representation of one of my improved shoes made from paper.

Figure 2 is a section of a shoe cut lengthwise through the centre.

In these drawings, A is the upper or top of the shoe, and a is the sole. In making my improved shoe I cut the upper or top A from such paper as I deem suitable, either in one or in several pieces, in the same or in a manner similar to that in which cloth or leather shoes are cut. I also cut a lining, if a lining is to be used; also, an outer and inner sole, if an inner sole is to be used. I now cement the upper or top together, if it is cut in more than one piece, and cement the lining into it, and apply the inner sole to a last, if an inner sole is used. If no inner sole is used, I apply the upper or top to the last, first moistening the inside and lower edges of the top so that the paper can be readily formed or pressed to the last, and after it is formed and the edges pressed to the last I apply some proper paste or cement to the edges of the top, which will be covered by the sole, or apply the cement to the sole, or to both the upper and sole, and then press the sole on to the edges of the upper on the last, and then apply some pressure to hold the sole on, either by drawing a strong cloth over the sole and last and securing it, or by applying pressure in some other way until it is dry. When an inner sole is used the upper is cemented to the inner sole and the outer sole cemented on afterward. After the shoe thus formed is dry the last may be taken out and the upper bound, if desired, or it may be bound before the sole is put in, if preferred:

I have described my improved shoe as being cemented, but it may be made by sewing or by both sewing and cementing, as may be preferred. My improved shoe may be made of enamelled paper, or of paper without being enamelled, and enamelled after it is made, or finished in some other way. My improved shoe can be made far cheaper than any shoes heretofore made in proportion to the service or wear that they are capable of enduring.

Having described my improved shoe, I claim as a new article of manufacture a shoe or slipper made of paper, substantially as described.

CHARLES R. BROADBENT.
